COMPRESSOR BLEED CONTROL

Carl F. Schorn, Detroit, Leonard W. Keil, Birmingham, and James A. McGrail and Philip M. Rogers, Royal Oak, Mich., assignors to Holley Carburetor Company, Detroit, Mich., a corporation of Michigan

Filed Oct. 10, 1955, Ser. No. 539,346

13 Claims. (Cl. 230—114)

This invention relates to gas turbines, and more particularly to compressor bleed systems for gas turbine engines.

Gas turbines, especially those adapted for use in propelling military aircraft, are often designed for optimum performance under predetermined conditions of operation. This being so, it is apparent that under other conditions of operation the performance of the engine may be something less than that to be desired.

In a gas turbine having a twin spool compressor, just for example, a low speed compressor supplies air to a high speed compressor, and the compressors or rotors as they are sometimes called are constructed so that the amount of air supplied for optimum engine performance is critical.

Failure to maintain this critical air flow through the compressors may result in serious malfunctions such as stalling of one or more stages of the compressor during acceleration or deceleration of engine speed. When stall occurs, engine operation becomes unstable, with surging flow and fluctuating discharge pressures resulting in serious vibration. This may be true, for example, when the low speed compressor supplies too much air to the high speed compressor, and one means of correcting this situation is to dump or bleed air from the low speed compressor.

The amount of air supplied by the low speed compressor is dependent mainly upon its speed and the temperature and pressure of the compressor inlet air.

Accordingly, one object of the invention is to provide an automatic and highly efficient and practical mechanical device that will continuously sense the speed of the low speed compressor, compressor inlet air pressure and compressor inlet air temperature and combine the effects thereof into a signal which will open or close a suitable compressor bleed valve at any desired speed, pressure or temperature condition.

Another object of the invention is to provide a mechanism of this kind which is pneumatically operated rather than oil operated. This is desirable because oil at higher temperatures tends to form varnishes and sludge which may foul delicate valves and other parts of the mechanism.

Still another object of the invention is to provide a device of this kind which is operated by compressor discharge pressure, which is already available in quantity.

A further object of the invention is to provide such a device having means for regulating compressor discharge pressure to provide a constant operating pressure.

A still further object of the invention is to provide a pneumatically operated device of this kind having means for metering the amount of compressor discharge air admitted in order to reduce the temperature within the device and to thus prevent damage to seals and other parts thereof.

Other objects of the invention will become more ap-

parent by reference to the following specification and attached drawings, wherein:

Figure 1 is a schematic cross sectional view, with portions thereof cut away, of a gas turbine engine equipped with a device embodying the invention;

Figure 2 is a longitudinal cross sectional view of the device shown schematically by Figure 1;

Figure 3 is a cross sectional view taken in the plane of line 3—3 of Figure 2, and looking in the direction of the arrows;

Figure 4 is an enlarged view of the upper portion of Figure 3 illustrating the structure in greater detail;

Figure 5 is an exploded perspective view illustrating in greater detail the means for combining the effects of the sensed conditions into a bleed control signal;

Figure 6 is a side plan view of the temperature compensating bellows arrangement shown in end view in Figures 1 and 3.

Referring to the drawings in greater detail, and to the schematic illustration in Figure 1 in particular, a gas turbine engine 10 having a compressor 12 with high and low speed rotors, a compressor air inlet passage 14 and a compressor discharge passage 16 is provided with a compressor air bleed control device 18.

As already stated above, the function of the device 18 is to sense the speed of the low speed compressor, compressor inlet air pressure and compressor inlet air temperature, and to signal one or more interstage air bleed valves 20 disposed in passages 22 to open or close as required in order to bleed the compressor 12 at any desired speed, pressure or temperature conditions.

For the purpose of sensing the above variables, the device 18 includes a temperature compensating system 24, an altitude (pressure) compensating system 26, a speed sensing system 28 and a speed set system 30. The device 18 is pneumatically operated by compressor discharge pressure, rather than by engine oil pressure; for this purpose, a compressor discharge air pressure regulating and metering system 32 is also provided. All of the above systems, which will be described individually, cooperate to produce the desired result, and they are preferably contained within a single housing 34.

The device 18 and the housing 34 may comprise any number of convenient sub-assemblies separated or enclosed by the usual resilient seals and secured by the usual fastening devices; such parts are well known in the art and will not be described unless necessary in order to describe the invention. Various conduits to be described in connection with the various systems may be provided between the engine 10 and the device 18.

Figure 1 is intended primarily to illustrate the relation between the engine 10 and the device 18 and between the various systems of the device 18, and not to accurately illustrate the details of construction of either the engine or the device.

Temperature compensating system

This system, which is best described by reference to Figures 1, 2 and 3, includes a thermostatic hollow bulb 36 which is preferably located in the number two position in the compressor air inlet 14 and which has a capillary tube 38 connecting it with a hollow thermostatic bellows 40. The bulb 36, tube 38, and bellows 40 are filled with a liquid, which varies in volume not only according to the temperature within the chamber 35 in the housing 34 but also according to the temperature of compressor inlet air as sensed by the bulb 36. A liquid filled ambient temperature bellows 42 compensates for the effect on bellows 40 by the temperature of the regulated compressor discharge control air in chamber 35 around the bellows 40 and 42.

Both of these bellows work against a spring load

which prevents vaporization within the bellows and supplies the return force when the sensed temperature is decreased. This spring force may be provided by resilient means such as compression springs 44 and 46. Each of bellows 40 and 42 have a support member 48 mounted thereon, each of which support members 48 is pivoted to an end of temperature bellows lever 50, which lever 50 is pivoted to end 52 of temperature cam lever 54. The central portion 56 of the temperature cam lever 54 is pivoted in bearing 58, and the opposite end thereof having the knob 60 is positioned in the slot 62 in the speed set cam 64.

It will be noted that bellows 40 is positioned side by side in respect to spring 46 and that bellows 42 is similarly positioned in respect to spring 44; in other words, the ends of the bellows 40 and 42 are offset in relation to one another. With this arrangement, expansion and contraction of the bellows 40 and 42 due to variations in the temperature in chamber 35 results merely in the pivoting of the lever 50 about its center. However, when a change in compressor inlet air temperature occurs, the lever 50 pivots about the pivots 66; this causes the temperature cam lever 54 to rotate the three-dimensional speed set cam 64 about shaft 68 for a purpose to be explained.

Altitude compensating system

This system is best shown by Figures 1, 3 and 4, and the main parts thereof are the evacuated aneroid bellows 70 having an internal expanding coil spring 72, the aneroid feedback spring 74 seated between the bellows 70 and the member 75 on the adjacent end 76 of the axially movable shaft 68 on which the speed set cam 64 is mounted, the aneroid servo valve 78 which is opened or closed by the lever 80 centrally pivoted at 82 and suitably mounted at one end thereof by means of a ball 84 between the bellows 70 and the spring seat 86, the aneroid slave restriction 88, the aneroid slave piston 90 which includes an axially movable guide member 92 and a high travel diaphragm 94 secured between the guide member 92 and the cylinder 96 and the aneroid slave spring 98 having one end thereof seated on the guide member 92.

Compressor inlet air pressure which is admitted to the chamber 100 from any desired position of the compressor 12 by means of conduit 102 is sensed by the aneroid bellows 70, adjustment of which is provided by screw 104. A load change on the bellows 70 unbalances the equilibrium between the bellows net force output and the aneroid feedback spring 74 and pivots the lever 80; this opens or closes the aneroid servo valve 78 so as to change the flow through the aneroid slave restriction 88. The change in flow changes the differential pressure across the aneroid slave piston 90 which in turn causes the speed set cam shaft 68 which is secured for movement with the aneroid slave piston 90 to change its axial position for a purpose to be described and the load of the aneroid feedback spring 74 to return the system to a balanced or null position.

Speed sensing system

The speed sensing system is best shown by Figure 2. It includes a drive gear 106 connected to rotate at a speed related to the speed of the low speed compressor, an outer governor shaft 108, radial ball bearings 110 and 112, a compressor bleed governor inner shaft 114, governor flyweights 116, a thrust ball bearing 118, a compressor bleed governor shaft bearing housing 120 and a governor spring 122. These elements are contained in the chamber 124 in the housing 34, the chamber 124 being vented to atmosphere by means of the check valve 126.

The drive gear 106 translates low speed compressor speed into outer governor shaft rotation 108 which causes the set position governor flyweights 116, so called be-

cause their movement is limited by the extent to which the end 128 of the bleed servo lever 132 can move, to exert an input force (parabolically proportional to the speed of the low speed compressor) to the speed set system 30 which is described below.

When the engine 10 is started, the drive gear 106 rotates the outer governor shaft 108 which causes the governor flyweights 116 to open until they assume a position determined by the force of governor spring 122. As speed increases, the flyweights 116 open further and eventually exert a force against the governor inner shaft 114, which force is in turn transmitted to the compressor bleed governor shaft bearing housing 120. This force causes the governor spring 122, seated on the compressor bleed governor shaft bearing housing 120, to compress when the force against the governor spring 122 becomes great enough to overcome the load preset in this spring. It is apparent then that the bleed servo lever link 130 which is pivoted to the housing 120 at 121 and to the bleed servo lever 132 at 133 moves according to the net applied governor flyweight force, and movement of the bleed servo lever link 130 causes rotation of the bleed servo lever 132 about the spaced pivots 134, the latter being the pivotal connection between lever 132 and the housing 124.

Speed set system

This system is best shown by Figures 2-5, and it is so termed because it utilizes the combined effects of inlet air pressure and temperature on the air bleed control mechanism to determine the speed of the low speed compressor (shaft 108) at which the bleed valve or valves 20 are to operate. The system includes the speed set cam 64, cam servo lever and support assembly 135, cam servo lever seat 136, cam servo sleeve 138, cam slave diaphragm 140, cam slave spring 142, speed set roller link assembly 144, speed set lever 148, speed set spring and seat assembly 150, speed set lever link 130, bleed servo lever 132, bleed servo valve 152 and bleed servo sleeve 154.

More specifically, the speed set system 30 functions to establish an equilibrium between the force of the flyweights 116 and a component of the force of the speed set spring 151, thereby allowing the bleed servo valve (or valves) 152 to assume predetermined positions.

The position of the speed set cam 64 changes, as already described above, in response to the temperature compensating system 24 and the altitude compensating system 26, and these changes cause the cam servo lever 158 to rotate about its supported end 160. The spring 162 eliminates play between the cam 64 and the cam follower 164. The cam servo seat 136 is pivoted on the free end 166 of the lever 158 so that the seat 136 aligns itself squarely on the adjacent end of the cam servo sleeve 138 as the cam follower 164, which may be integral with the end of the lever 158, senses cam lift changes.

Changes in the position of the cam servo seat 136, relative to the cam servo sleeve 138, permit a change in the differential pressure across the cam slave diaphragm 140, due to the passages 168 and 169 in the sleeve 138 providing communication between the chamber 35 and the chamber 172 which is vented by passage 173. The cam servo sleeve 138 moves with the diaphragm 140 and its support 174 in response to this differential change in order to re-establish the equilibrium position of the sleeve 138 relative to the seat 136. The cam servo sleeve 138 is linked to the speed set roller link assembly 144, so that movement of the sleeve 138 results in movement of the assembly 144.

The rollers 176 on the speed set roller link assembly 144 function as a movable low friction fulcrum between the speed set lever 148 and the bleed servo lever 132, and the variable flyweight force, a measure of the speed of the low speed compressor, is balanced by the constant force of the speed set spring 151 with the help of this

movable fulcrum. The rollers 176 on the assembly 144 cause the constant force of the speed set spring 151 to be applied at a variable position in such a way that the effect of this spring force increases hyperbolically as the rollers 176 approach the speed set lever pivot 180, at which the speed set lever 148 is pivoted to the housing 124.

The rotation of the bleed servo lever 132, one or more arms 182 of which may be pivotally connected to one or more bleed servo valves 152, results in axial movement of the bleed servo valves 152 within the bleed servo sleeves 154 in a manner to cause compressor discharge air supplied by the line 184 to the bleed servo valve inlet 186 to move the piston 188 of each compressor bleed valve actuator 190 in the desired direction for opening or closing the bleed valves 20 located on the engine 10.

Compressor discharge air pressure regulating and metering system

This system, which is best shown by Figure 3, regulates and at the same time meters the comparatively warm variable pressure compressor discharge air supplied through conduit 184 to provide the minimum amount of control air at a given constant pressure above atmospheric pressure necessary for operating the air bleed control device 18. The system includes a compressor discharge air pressure regulating bellows 192, a pressure regulating valve 194 attached for movement with the bellows 192 and a valve seat 196.

Bellows 192 is internally vented to atmospheric pressure through the passages 198 and 200. Unregulated compressor discharge pressure, which enters the chamber 202 from the branch line 204, is confined upstream of the pressure regulating valve 194 and outside of the bellows 192. This unregulated pressure does not exert force effective to compress the bellows 192, or to open the valve 194, because the bellows effective area is exactly matched by the area of the valve 194 disposed within the metering diameter of the valve seat 196. In other words, the effect of unregulated compressor discharge pressure is eliminated.

It will be apparent that the bellows 192 may be adjusted by means such as the adjustment screw 206 so that the position of the bellows 192, and the valve 194, is determined by the effect of the desired regulated pressure within chamber 35, 15-20 p.s.i. above atmospheric for example, acting over the effective area of the bellows 192 against the rate of the bellows spring 208.

Since the pressure regulating valve 194 is in series with the air flow path, this system also functions as a throttling means, restricting the flow of compressor discharge air at the same time that a constant pressure drop is maintained in the device 18 between the chamber 202 and the outlet 210.

The following formula, wherein

$$\begin{aligned} P_4 &= \text{unregulated compressor discharge pressure;} \\ A_1 &= \text{metering area of valve 194;} \\ P_1 &= \text{control pressure within chamber 35;} \\ A_2 &= \text{metering area of jet 88;} \\ P_2 &= \text{pressure regulated by the aneroid servo 78;} \\ A_3 &= \text{metering area of the aneroid servo 78;} \\ P_3 &= \text{pressure regulated by the cam servo seat 136;} \\ A_4 &= \text{metering area of the cam servo sleeve 138;} \end{aligned}$$

indicates that the valve 194 responds both to changing P_4 pressure and to the changing flow of air through the device 18:

$$\text{Flow} = K_1 A_1 \sqrt{P_4 - P_1} = K_2 A_2 \sqrt{P_1 - P_2} + K_3 A_3 \sqrt{P_3 - \text{atmosphere}} + K_4 A_4 \sqrt{P_3 - \text{atmosphere}}$$

Thus, the system 30, in addition to regulating control pressure reduces the amount of hot compressor discharge air introduced into the chamber 35 to the minimum required for operation of the device 18, thereby reducing

the operating temperature thereof. The above described advantages of pneumatic operation are obtained without the obvious disadvantages of higher operating temperature that would result if this type of metering were not provided for.

It is apparent from the above specification and the attached drawings that there has been provided a completely automatic, pneumatically operated mechanical device which continuously senses the speed of the low speed compressor, compressor inlet air temperature and compressor inlet air pressure. The device then combines the effects of these important variables into a single continuous signal which is used to bleed the compressor whenever necessary to extend the optimum performance of a gas turbine engine over a wider range of operating conditions.

The device is easily adaptable to bleed any desired stage of any type of compressor in any desired amount. The device is also adaptable to perform any other operation which is dependent upon the above variables in connection with a gas turbine engine or any other device.

While the invention is disclosed in a single preferred embodiment thereof, it is apparent that certain changes may be made therein within the scope of the invention, and no limitations are intended except as may be required by the appended claims.

What is claimed is:

1. The combination of a gas turbine engine having a casing forming compressor air inlet and discharge passages and an air bleed opening therebetween, bleed valve means in said opening for bleeding air from said compressor and a compressor bleed control device for opening and closing said bleed valve means, said device comprising double-acting actuator means operated by unregulated compressor discharge air connected to and operating said bleed valve means, servo valve controlled conduit means directing unregulated compressor discharge air to said actuator means, a housing formed to provide first and second chambers sealed from one another by a flexible diaphragm, mechanical means in said first chamber for sensing compressor speed, mechanical means in said first chamber for operating said servo valve means, said two means in said first chamber being operatively connected, means in said second chamber for sensing compressor air inlet pressure, separate means in said second chamber for sensing compressor inlet air temperature, said temperature sensing means being insensitive to variations in control ambient temperature, said pressure and temperature sensing means being connected to and operating a three-dimensional cam combining said pressure and temperature signals, means operatively connected through said flexible diaphragm and between said cam and said mechanical means operating said servo valve means for utilizing said combined pressure and temperature signals to determine the compressor speed at which said bleed valve means shall open and close, said latter means and said pressure-sensing means being operated by regulated compressor air discharge pressure in said second chamber, a conduit supplying compressor discharge air to said second chamber, and means for regulating the pressure and metering the quantity of said compressor discharge air supplied to said second chamber.

2. The combination of a gas turbine engine having a casing forming compressor air inlet and discharge passages and an air bleed opening therebetween, bleed valve means in said opening for bleeding air from said compressor and a compressor bleed control device for opening and closing said bleed valve means, said device comprising double-acting actuator means operated by unregulated compressor discharge air connected to and operating said bleed valve means, servo valve controlled conduit means directing unregulated compressor discharge air to said actuator means, a housing formed to

provide first and second chambers sealed from one another by a movable wall, means in said first chamber sensing compressor speed, means in said first chamber operating said servo valve means, said two means in said first chamber being operatively connected, means in said second chamber sensing compressor air inlet pressure, separate means in said second chamber sensing compressor inlet air temperature, said temperature sensing means being compensated for variations in control ambient temperature, said pressure and temperature sensing means being connected to and operating a three-dimensional cam combining said pressure and temperature signals, means operatively connected through said movable wall and between said cam and said means operating said servo valve means for utilizing said combined pressure and temperature signals to determine the compressor speed at which said bleed valve means opens or closes, said latter means and said pressure sensing means being operated by regulated compressor air discharge pressure in said second chamber, a conduit communicating between said compressor discharge passage and said second chamber, and means in said conduit for regulating the pressure and metering the quantity of said compressor discharge air contained in said second chamber.

3. In a gas turbine engine having a casing forming compressor air inlet and discharge passages and an air bleed opening therebetween, and bleed valve means in said opening for bleeding air from said compressor, a compressor bleed control device for opening and closing said bleed valve means, said device comprising actuator means operated by unregulated compressor discharge air connected to and operating said bleed valve means, servo valve controlled conduit means directing unregulated compressor discharge air to said actuator means, a housing formed to provide first and second chambers sealed from one another by a pressure responsive member, means in said first chamber sensing compressor speed, means in said first chamber operating said servo valve means, said two means in said first chamber being operatively connected, means in said second chamber sensing compressor air inlet pressure and compressor inlet air temperature, said temperature sensing means being insensitive to variations in control ambient temperature, said pressure and temperature sensing means being connected to and operating a three-dimensional cam, said cam combining said pressure and temperature signals, means operatively connected through said pressure responsive member and between said cam and said mechanical means operating said servo valve means for utilizing said combined pressure and temperature signals to determine the compressor speed at which said bleed valve means opens and closes, said latter means and said inlet air pressure sensing means being operated by regulated compressor air discharge pressure supplied to said second chamber by a conduit, and means in said conduit for regulating the pressure and metering the quantity of said compressor discharge air in said second chamber.

4. In a turbine engine compressor bleed control, a compressor casing having an air bleed opening, a variably positioned, pneumatically operated valve in said opening adapted to discharge air in excess of that required for optimum compressor operation, means responsive to compressor speed operatively connected to position said valve, and means responsive to compressor inlet temperature and operating conjointly with means responsive to compressor inlet pressure operatively connected with said first means to modify the action of said speed responsive means and to vary the range during which said speed responsive means is effective to control said valve, said latter means being powered by compressor discharge air.

5. In a compressor air bleed control for a gas turbine engine having a compressor case with an air bleed opening, a pneumatically actuated air valve in said opening

for bleeding excessive quantities of air from one or more stages of said compressor, a mechanically operated servo valve controlling the pneumatic forces to said air valve, a three-dimensional cam operatively connected to said servo valve, means responsive to compressor inlet temperature and operatively connected so as to determine the position of said cam, means responsive to compressor inlet pressure connected to modify the position of said cam as determined by said temperature responsive means, and means responsive to compressor speed operatively connected to said servo valve and having movement as a function of changes in compressor speed for selecting the point at which said air valve is operable.

6. A compressor bleed device for a gas turbine engine having a compressor case formed to provide compressor air inlet and discharge passages and an air bleed opening therebetween, comprising an air valve in said opening, a double acting pneumatic actuator connected to a source of unregulated compressor discharge air and to said valve in a manner so as to be adapted to open and close said valve, a servo valve controlled conduit connected between said source of unregulated compressor discharge air and said actuator, said servo valve controlling the flow of said unregulated compressor discharge air through said conduit to said actuator, separate means each sensing one of three variables including compressor speed and compressor air inlet temperature and pressure, a second conduit leading from said compressor discharge passage, means in said second conduit for providing a metered supply of regulated compressor discharge air pressure, one or more of said separate means being powered by said regulated compressor discharge air pressure, and means also powered by said regulated compressor discharge air pressure combining the effect of each of said separate sensing means and effective through its connection with said separate means and with said servo valve to control the position of said air valve in response to said three variables.

7. A compressor bleed device for a gas turbine engine having a compressor case formed to provide compressor air inlet and discharge passages and an air bleed opening in said case, comprising an air valve in said opening, a double acting pneumatic actuator connected to a source of unregulated compressor discharge air and to said valve in a manner so as to be adapted to open and close said valve, a servo valve controlled conduit connected between said source of unregulated compressor discharge air and said actuator, said servo valve controlling the flow through said conduit of said unregulated compressor discharge air to said actuator, separate means each sensing one of three variables including compressor speed and compressor air inlet temperature and pressure, a second conduit leading from said compressor discharge passage, means in said second conduit for providing a metered supply of regulated compressor discharge air pressure, one or more of said separate means being powered by said regulated compressor discharge air pressure, and means also powered by said regulated compressor discharge air pressure combining the effect of each of said separate sensing means and effective through its connection with said separate means and with said servo valve to control the position of said air valve in response to said three variables.

8. A compressor bleed device for a gas turbine engine having a compressor case formed to provide compressor air inlet and discharge passages and an air bleed opening in said case, comprising an air valve in said opening, a double acting pneumatic actuator connected to a source of unregulated compressor discharge air and to said valve in a manner so as to be adapted to open and close said valve, a servo valve connected between said source of unregulated compressor discharge air and said actuator, said servo valve controlling the flow of said unregulated com-

pressor discharge air to said actuator, a housing containing separate means each sensing one of three variables including compressor speed and compressor air inlet temperature and pressure, said means sensing air inlet temperature having means to eliminate the effect of varying ambient temperature in said device, a conduit between said compressor discharge passage and said housing, means in said conduit for providing a metered supply of regulated compressor discharge air pressure, one or more of said separate means being powered by said regulated compressor discharge air pressure, and means also powered by said regulated compressor discharge air pressure combining the effect of said separate sensing means and effective through its connection with said separate means and with said servo valve to control the position of said air valve in response to said three variables.

9. A compressor bleed device for a gas turbine engine having a compressor case formed to provide compressor air inlet and discharge passages and an air bleed opening in said case, comprising an air valve in said opening, a double acting pneumatic actuator connected to a source of unregulated compressor discharge air and to said valve in a manner to be adapted to open and close said valve, a servo valve connected between said source of unregulated compressor discharge air and said actuator, said servo valve controlling the flow of said unregulated compressor discharge air to said actuator, a housing containing separate means each sensing one of three variables including compressor speed and compressor air inlet temperature and pressure, a conduit between said compressor discharge passage and said housing, means in said conduit for providing a metered supply of regulated compressor discharge air pressure, one or more of said separate means being powered by said regulated compressor discharge air pressure, and means also powered by said regulated compressor discharge air pressure combining the effect of said separate inlet air temperature and pressure sensing means and effective through its connection with said separate speed sensing means and with said servo valve to control the position of said air valve in response to said three variables.

10. A compressor bleed device for a gas turbine engine having a compressor case formed to provide compressor air inlet and discharge passages and air bleed opening in said case comprising and air valve in said opening, a double acting pneumatic actuator connected to a source of unregulated compressor discharge air and to said valve in a manner so as to be adapted to open and close said valve, a servo valve connected between said source of unregulated compressor discharge air and said actuator, said servo valve controlling the flow of said unregulated compressor discharge air to said actuator, a housing containing separate means each sensing one of three variables including compressor speed and compressor air inlet temperature and pressure, a conduit between said compressor discharge passage and said housing, means in said conduit for providing a metered supply of regulated compressor discharge air pressure, one or more of said separate means being powered by said regulated compressor discharge air pressure, and means also powered by said regulated compressor discharge air pressure combining the effect of said separate inlet air temperature and pressure sensing means and effective through its connection with said separate speed sensing means and with said servo valve to control the position of said air valve in response to said three variables, said connection with said speed sensing means including a spring and lever mechanism providing a mechanical advantage causing the fixed force of said spring to be effectively changed parabolically with changes in compressor inlet temperature or pressure.

11. In a gas turbine engine having a compressor casing formed to provide compressor air inlet and discharge passages and a compressor air bleed opening, a device for bleeding compressor air through said opening, said

device comprising a valve in said opening, a two-way pneumatic actuator connected to said valve and to a source of unregulated compressor discharge air pressure, a servo valve connected between said actuator and said source of unregulated air pressure and controlling the flow of said air to said actuator, first means for producing a continuous signal in response to compressor air inlet temperature, the signal from said first means not including any effect of changes in ambient temperature in said device, second means for producing a continuous signal in response to compressor air inlet pressure, a three-dimensional cam connected to said first and second means in a manner so that the position thereof is dependent upon a compressor air inlet temperature and pressure, third means for producing a continuous signal in response to compressor speed, a housing for said signal producing means, a conduit between said compressor discharge passage and said housing, means in said conduit supplying a metered source of regulated compressor discharge air pressure, and means responsive to cam position and to said compressor speed signal connected to and controlling said servo valve, said latter means being actuated by regulated compressor discharge air pressure.

12. In a gas turbine engine having a compressor casing formed to provide compressor air inlet and discharge passages and a compressor air bleed opening, a device for bleeding compressor air through said opening, said device comprising a valve in said opening, a two-way pneumatic actuator connected to said valve and to a source of unregulated compressor discharge air pressure, a servo valve connected between said actuator and said source of unregulated air pressure and controlling the flow of said air to said actuator, first means for producing a continuous signal in response to compressor air inlet temperature, said first means being arranged so as to eliminate the effect of changes in ambient temperature in said device, second means for producing a continuous signal in response to compressor air inlet pressure, third means for producing a continuous signal in response to compressor speed, a three-dimensional cam connected to two of said means in a manner so that the position thereof is dependent upon the respective signals produced thereby, a housing for said signal producing means, a conduit between said compressor discharge passage and said housing, means in said conduit supplying a metered source of regulated compressor discharge air pressure, and means responsive to cam position and to the other of said signals connected to and controlling said servo valve, said latter means being actuated by regulated compressor discharge air pressure.

13. In a gas turbine engine having a compressor casing formed to provide compressor air inlet and discharge passages and a compressor air bleed opening, a device for bleeding compressor air through said opening, said device comprising a valve in said opening, a two-way pneumatic actuator connected to said valve and to a source of unregulated compressor discharge air pressure, a servo valve connected between said actuator and said source of unregulated air pressure and controlling the flow of said air to said actuator, first means for producing a continuous signal in response to compressor air inlet temperature, said first means being arranged so as to eliminate the effect of changes in ambient temperature in said device, second means for producing a continuous signal in response to compressor air inlet pressure, a three-dimensional cam connected to said first and second means in a manner so that the position thereof is dependent upon compressor air inlet temperature and pressure, third means for producing a continuous signal in response to compressor speed, said third means including a centrifugal governor and a spring arranged so that the output force of said spring is parabolically proportional to compressor inlet temperature or pressure, a housing for said signal producing means, a conduit having

11

means supplying metered and regulated compressor discharge air pressure to said housing, and means responsive to cam position and to said compressor speed signal connected to and controlling said servo valve, said latter means being actuated by regulated compressor discharge air pressure.
